KEY RING TAG

Boris Blecher, Philadelphia, Pa.

Application April 8, 1952, Serial No. 19,251

Term of patent 14 years

(Cl. D45—15)

To all whom it may concern:

Be it known that I, Boris Blecher, a citizen of the United States and a resident of Philadelphia, county of Philadelphia, State of Pennsylvania, have invented a new, original, and ornamental Design for a Key Ring Tag, of which the following is a specification, reference being had to the accompanying drawings, forming a part thereof, wherein:

Figure 1 is a front elevational view of one face of the key ring tag, showing my new design;

Figure 2 is an edge elevational view thereof; and

Figure 3 is a view showing the tag in open condition.

The characteristic feature of my design resides in the combination on a laminated key ring tag having the configuration disclosed of the specific recess on one of the inner faces in association with the pictorial symbols arranged about said recess, all as shown.

The side opposite Fig. 1 is the same as that shown.

I claim:

The ornamental design for a key ring tag, as shown and described.

BORIS BLECHER.
